EXTENSION ATTACHMENT FOR BOATS

Emil S. Anderson, Chicago, Ill.

Application July 24, 1947, Serial No. 763,254

3 Claims. (Cl. 114—66.5)

1

The invention relates to an attachment for the hull of a power driven boat and particularly a boat driven by an outboard motor.

Hulls for outboard motors are built by certain builders while the motors are manufactured by other manufacturers. Because of this fact, a purchaser of a hull and motor rarely obtains a combination thereof in which the two are truly balanced. It also frequently occurs that the owner of an outboard motor boat wishes to utilize a heavier and more powerful motor on a hull that is primarily designed for a lighter, less powerful motor. Such a hull with the heavier motor obviously will not give good performance, particularly when an attempt is made to operate it at higher speeds. Longitudinal oscillation or "porpoising" may occur as well as lack of stability and other difficulties.

The general object of the invention is therefore to provide an attachment for such a hull, which has the effect of dampening such longitudinal vibration and adds materially to the running stability of the boat, particularly in the case where a relatively heavy, powerful motor is utilized.

More specifically, it is an object of the invention to provide an extension, in the form of a readily applied attachment for the hull of a boat used with an outboard motor, the extension providing an increase in the effective length of the hull, thus gaining the advantage of a larger hull.

Another object is to provide an extension of the foregoing general character, which is adjustable to the most effective operating position for a given combination of hull and motor.

A further object is to provide an extension of the foregoing character, which may be so related to the hull bottom as to give it the advantages of the so-called "step-bottom" hull.

Other objects and advantages will become apparent from the following description, taken in connection with the accompanying drawings, in which:

Figure 1 is a perspective view of a boat driven by an outboard motor and provided with an extension attachment embodying the features of the invention.

Fig. 2 is a rear view of the boat with the attachment.

Fig. 3 is a fragmentary side elevational view of the boat with the attachment.

Fig. 4 is a horizontal sectional view taken on the line 4—4 of Fig. 3.

As heretofore mentioned, it rarely occurs that the owner of an outboard motor boat has a hull

2

which is truly balanced and coordinated with the motor used with such hull. Also, such an owner may frequently attempt to use a motor which is much more powerful and heavier than the hull is primarily designed for. The present invention provides an attachment for such a hull which has the effect of lengthening the hull and thereby dampening tendencies of the hull to undergo longitudinal oscillation or porpoising when driven by such a high-powered motor. The present attachment also provides a means whereby adjustment thereof may bring the hull into a reasonably balanced relation with the motor so that the two cooperate with the maximum effect.

15 The present device further provides attainment of the beneficial effects of the so-called step-bottom hull.

Generally described, the attachment comprises a plate-like structure adapted to be attached to 20 the transom of the hull which constitutes, in effect, an extension of the bottom of the boat. The plate-like structure is angularly adjustable relative to the hull so that the most effective operating position may be obtained. The attachment 25 of the plate-like structure to the hull is also so placed as to give the step-bottom effect.

In the drawing, I have shown a boat, the hull of which is indicated generally at 10 and which includes a transom 11. No particular boat structure is claimed, but it may be stated that the type illustrated is one which is frequently used with outboard motors. Mounted on the transom by means of a clamp, as is usual, is an outboard motor, indicated generally at 12, the propeller shaft casing of the motor extending downwardly 30 so that the propeller, indicated at 13, is below the bottom of the hull.

The hull bottom, when the boat is operating at substantial speed, provides a planing action tending to lift the boat and causing it to operate more or less at the surface of the water. With a motor which is of higher power than that for which the hull is primarily designed, longitudinal vibration or porpoising of the hull may occur at substantial speeds. This is largely due to the length of the planing surface or bottom of the boat in relation to the power of the motor and speed of operation thereof. A longer hull would, of course, eliminate such difficulty, but actual elongation of the hull itself would be difficult, if not impractical to attain.

The present device is in the form of an attachment which may be readily applied to the transom 11 to give the effect of increased length to the hull. To this end, I provide a plate structure,

indicated generally at 20, attached to the transom 11 adjacent the bottom edge thereof and extending rearwardly therefrom. The plate structure thus operates substantially as a continuation of the bottom of the boat to give the effect of increased length. Because the motor 12 is mounted directly on the transom 11, the plate structure is provided centrally with an opening or gap to permit the propeller drive to extend downwardly therethrough. In the present instance, I have found it simpler to make the plate structure 20 in the form of two separate plates 21 mounted on opposite sides of the propeller shaft casing. In its preferred form, each plate 21 is of sufficient area so that it extends from a point near the longitudinal center line of the boat laterally, substantially to the side edge of the boat. The two plates 21 thus together form a continuation of the bottom of the boat except for the central area between the plates through which the propeller drive casing of the motor extends. Each plate 21 is held in position by being attached at its front edge to the transom and having a brace, indicated generally at 22, attached at its front end to the transom and at its rear end to the plate adjacent the rear edge thereof.

In order to permit the plate structure to be adaptable to different hulls and different motors with the idea of obtaining the best conditions of balance for each, I provide for adjustment of the plate structure in its angular relation to the bottom of the hull. To this end, while the angularity of the plate might be varied by making it of relatively flexible metal, I have shown the plates 21 as being secured to the transom at their front edges by means of hinges 23. The braces are also made adjustable so as to be able to swing the plate 21 on its hinges 23. In the present instance, each brace 22 is in the form of an inverted Y with the ends of the arms of the Y pivotally secured to the plate 21 adjacent the rear edge thereof by means of brackets 24. The stem of the Y is pivotally secured to the transom 11 by means of a bracket 25 spaced upwardly from the hinges 23. The stem of the Y is also made extensible by means of a telescoping structure comprising a tubular portion 26 and a rod 27 slidably mounted therein and pivoted on the bracket 25. A setscrew 28 may be provided for holding the tubular portion 26 and rod 27 rigidly in adjusted position. To gain the step-bottom effect, the hinges 23 are spaced a short distance above the bottom edge of the transom 11 so that the front edge of the plates 21 thus form a step with the bottom of the hull.

The attachment above described may be readily secured to the transom of the boat merely by screws or the like. After placing such attachment on the boat, the preferred angular position of the plates 21 may be determined by trial. Thus, the telescoping construction of the braces 22 may be adjusted to different positions until the position is found where longitudinal vibrations or porpoising are reduced to a minimum. The attachment is relatively light in weight and consequently does not add greatly to the overall weight of the hull, but it does have the effect of providing a substantial increase in the planing surface or bottom of the hull. The attachment thus provides a simple means for adapting motors of various sizes to a given hull structure.

5 I claim:

1. An attachment for an outboard motor boat of the type having a substantially flat bottom and a transom extending upwardly from the rear edge of the bottom, said attachment comprising a pair of plates adapted to extend rearwardly from the transom on opposite sides of the motor adjacent the bottom of the boat and providing a plane surface constituting an extension of the bottom, hinge means mounted at the front edge of said plates for pivotally connecting the plates to the transom, and a pair of braces for the respective plates, each having the shape of an inverted Y with the ends of the arms of the Y pivotally connected to one of the plates adjacent opposite side edges thereof, the stem of the Y being adapted to be pivotally secured to the transom and having a telescoping construction to provide for adjustment in length, whereby the angular relation of the plates to the bottom of the boat may be adjusted to attain longitudinal balance for the boat.
2. In an outboard motor boat of the type having a substantially flat bottom and a transom extending upwardly from the rear edge of the bottom, an attachment comprising a plate structure adapted to extend rearwardly from the transom with its front edge spaced above the bottom of the boat to provide a stepped bottom effect, and means for connecting the plate structure to the transom including adjustable bracing means for varying the angular relation of the plate structure to the bottom of the boat whereby to attain longitudinal balance for the boat.

3. In an outboard motor boat of the type having a substantially flat bottom and a transom extending upwardly from the rear edge of the bottom, an attachment comprising a plate structure adapted to extend rearwardly from the transom, means for attaching said plate structure to the transom with the front edge of said plate structure spaced above the bottom of the boat to provide a stepped bottom effect, and adjustable bracing means connected to the transom and to said plate structure adjacent the opposite side edges of the latter for varying the angular relation of the plate structure to the bottom of the boat whereby to attain longitudinal balance for the boat.
